UNITED STATES PATENT OFFICE.

JOSEPH A. McLANE, OF WASHINGTON, DISTRICT OF COLUMBIA, ASSIGNOR TO ULTRATEX PRODUCTS COMPANY, A CORPORATION OF MAINE.

WEFTLESS TIRE-FORMING CORD BAND.

Application filed January 13, 1923. Serial No. 612,378.

To all whom it may concern:

Be it known that I, JOSEPH A. McLANE, a citizen of the United States, residing at Washington, in the District of Columbia, have invented certain new and useful Improvements in a Weftless Tire-Forming Cord Band, of which the following is a specification.

This invention relates to a form of textile for the production of a weftless cloth for use in the making of rubberized material particularly designed for the construction of the carcass of pneumatic tire casings and of the general type known as cord tires. In this type of tire the distinguishing characteristic has been to retain a weft weave only for the purpose of temporarily holding the cords or warps parallel and in sheet formation, and are used in greater or less number, the presence of which in the manufactured rubberized cloth causes lack of uniformity an insufficient tension and undulations of the cords, imperfect coating of the cords with rubber with consequent weak spots and separation of the rubber from the cords, besides producing a source of frictional heat and other objectionable features in the tire built of this form of weft cord cloth.

The object therefore of the present invention is to eliminate the weft threads from the rubberized cloth and avoid all the consequent disadvantages due to the presence of weft threads in tires, as well as the saving of the cost of the weft threads and the weaving cost thereof, and the making of a form of weftless cord bands that can be produced by the textile manufacturer in beamed form with a saving in weight of square yardage over the existing practice and the making unnecessary of the tedious hand-tying operation required in beaming a large number of cords, while at the same time a form of cord band is produced suitable for frictioning directly through the rolls of a calendar by reason of the means by which the cords are held in their proper parallel and equally stressed condition in the initial winding on the beam and the unwinding therefrom upon a wind-up roll for drawing the same through the calendering machine.

For the attainment of the above stated object the invention consists in a band of cords terminating at one end in a flexible winding portion preferably of fabric weave

to provide a flexible header for beginning the winding on the beam, and at its other end with a similar flexible winding portion for starting the winds on the usual wind-up roll, so that all the cords will be maintained accurately spaced and no undue skill or time required in the operation of beaming or installing a beam and connecting the band with its wind-up roll in readiness for drawing the same through the calender. In the beaming of these cord bands with their terminal fabric ends, the cords will pass from their spools through a loom that will be operated to weave a portion of the bands only where the fabric ends are desired, and for the purpose of beaming short band lengths of 150 yards or other commercial length, the terminal fabric portions may be made by intermediate weaving of the bands and the cutting through the same to divide the fabric portion and form fabric end portions.

The present invention is especially designed for use in connection with the special method of apparatus forming the subject of an application filed of even date herewith and bearing Serial No. 612,377, and the method and apparatus forming the subject matter of Letters Patent issued June 20, 1922, No. 1,420,271.

In the accompanying drawings,

Figure 1 illustrates the weftless cord band having the terminal fabric ends, and

Figure 2 illustrates a length of band to be cut into several lengths by cutting through the intermediate fabric weaving to form end fabric portions for the shorter lengths.

Referring to the drawings, 10 indicates the cords of the weftless band and 11 the fabric terminal portion of the band. Except for these terminal portions the cords are free of any cross support, but under the winding and spacing initiated by the fabric end portions and the equal tension resulting from the uniform stress of the wound woven portion as an attaching and drawing means these free cords are maintained in their sheet formation, so that in calendering or in impregnating they will not be caused to overlap each other or form in the rubberized cloth what are known as hard and soft spots but produce a uniform product.

When it is desirable to form the short

lengths for convenient shipping to and use by the trade the intermediate fabric portions 11^a are made and cut through on the line *a—a* to form end fabric portions for 5 the shorter lengths.

It will be seen that by this form of cord band a product is finished that, both from the textile producing end and the use thereof in forming weftless rubber cloth, presents 10 many economies and advantages, and with the further results that a superior tire may be constructed therefrom and at less cost and labor.

What I claim, is:

- 15 1. A textile article of manufacture for the continuous production of weftless rubberized cloth therefrom during the passage of the same through suitable rubber-applying means, said article comprising a multiplicity of cords or warps arranged in parallel relation to form a weftless band of relatively great length and terminating in woven sections at each end adapted to provide means for maintaining the cords or 20 warps in flat parallel relation and furnish a wind-up portion upon which the cords of the unwoven length of the band are wound in parallel relation and maintained in such relation in the winding.
- 25 2. A textile article of manufacture for the continuous production of weftless rubberized cloth therefrom during the passage of the same through suitable rubber-applying means, said article comprising a multiplicity of cords or warps arranged in par-

allel relation to form a weftless wound band thereof of relatively great length terminating in a transverse woven portion at one end and connecting the cords or warps in flat parallel relation and adapted to provide a wind-up portion for the initial winding of the band, and a terminal transverse portion connecting the cords or warps together in band-formation at the other end, whereby the cords or bands in being 40 unwound and rewound will travel during the application of the rubber in uniform band formation.

3. The method of forming a band of parallel cords of relatively great length for 50 the continuous production of weftless rubber cloth therefrom by suitable rubber-applying means during the passage of the band of cords therethrough, which method consists in first weaving the cords to form a fabric section for connecting them in their parallel band formation, winding the cords in such formation upon the fabric section, weaving at intermediate points of the band of cords other woven sections, to 55 form therebetween a band section of the cords of relatively great length, and cutting through the intermediate woven sections to form the commercial lengths of the band with a fabric wind-up section at each end thereof, as and for the purpose set forth.

In testimony whereof I affix my signature.

JOSEPH A. McLANE.
